BILLET HANDLING DEVICE FOR TUBE MILLS

Walter J. Assel, Canton, Ohio, assignor to The Timken Roller Bearing Company, Canton, Ohio, a corporation of Ohio

Application June 20, 1938, Serial No. 214,712

10 Claims. (Cl. 80—11)

My invention relates to tube mills of the cross-roll type wherein a pierced billet is supported interiorly by a mandrel during the rolling operation. The principal objects of the invention are to facilitate and expedite the handling of the pierced billet between the piercing mill and the pass of the rolling mill, including the preparatory straightening of the billet, the entry of the mandrel into the billet, the guiding of the billet into the pass and the preventing of whipping of the billet. The invention consists in the construction hereinafter described and claimed.

In the accompanying drawings wherein like reference numerals refer to like parts wherever they occur,

Fig. 1 is a plan view and Fig. 2 is a side elevation of a construction embodying my invention;

Fig. 3 is a view thereof partly in end elevation and partly in vertical cross section on the line 3—3 of Fig. 2. In this Fig. 3, the lid of the guide trough is shown in three positions, namely, in guiding position indicated by full lines, in billet clamping position indicated by broken lines and in open position indicated by dot and dash lines.

Fig. 4 is a horizontal sectional view of a portion of the apparatus on the line 4—4 of Fig. 3;

Fig. 5 is a sectional detail view on the line 5—5 of Fig. 3; and

Fig. 6 is a sectional detail view on the line 6—6 of Fig. 3.

My device comprises an elongated frame 1 with a horizontal trough member 2 which, in practice, is located on the entering side of the cross-roll mill and in alignment with the pass line thereof. As the height of the pass line changes with the diameter of the work piece, the trough member of my device is made separate from the frame so as to be vertically adjustable. For this purpose, I prefer to interpose shims 3 between the frame and the bottom of the trough member.

Above the trough is an inverted channel-shaped member which serves as a movable lid 4 therefor. This lid has pairs of arms 5, 6 that extend laterally from one side thereof and are pivotally mounted on brackets 7, 8 provided therefor on the frame. Preferably the end portions of the lid arms are provided with holes for pivot pins 9, 10, respectively, that extend through them and through aligned holes provided therefor in the respective brackets, thereby forming horizontal hinges upon which the lid can

swing upwardly far enough to permit a billet A to enter sidewise between the trough and the lid.

Both or one of the hinge arms 5 of the lid is extended beyond its pivot pin and is pivotally connected by a pivot pin 25 to the rod 11 of a piston 31 in a cylinder 12 (hereinafter called the main cylinder) which is journaled on horizontal trunnions 13 which have bearings on the frame. On opposite sides of its piston, the main cylinder 12 is provided with ports that are connected by suitable pipes 14 with a source of fluid pressure, preferably air pressure, and suitable means (not shown) are provided for controlling the admission and release of air into and out of said cylinder. With this arrangement, the hinge arm 15 5 of the trough lid constitutes a lever that may be raised and lowered by the air pressure in said main cylinder.

When the main piston goes down, its rod 11 pulls down the outer end of the hinge lever 5 and thereby raises the lid to its fully open position ready to admit a billet sidewise into the trough. When the piston of the main cylinder 12 is raised, its rod 11 pushes up the hinge lever 5 and causes the trough lid to close and, in doing so, to press against and straighten the billet in said trough. In this closed position, the billet A is held firmly by the lid and, while so held, the mandrel B is inserted endwise into the billet by mechanism of a well-known type that is outside 30 of the present invention.

When the mandrel is inserted in the billet, the pressure of the lid thereon is released and the lid lifted slightly to clear the mandrel and permit the billet to slide along the trough but 35 in order to guide the billet and prevent it from whipping, the lid, in its partly open or guiding position, should still be close to the billet. For this purpose, a second cylinder 15 (hereinafter called the lid positioning cylinder) is provided. 40 This lid-positioning cylinder is preferably pivotally mounted on horizontal trunnions 16 and is provided with a piston, ports, passageways 17 communicating with a source of air pressure and means for controlling the same similar to those 45 above described in connection with the first cylinder.

The piston rod 18 of the lid positioning cylinder is pivotally connected to a lever 19, one end of which is bifurcated and provided with pivot 50 holes through which extends the horizontal pivot pin 9 that serves to connect the hinge lever 5 of the lid member to the bracket 7. The other end of said lever 19 has a vertical hole there-through which is threaded to receive an adjust-

ing screw 20 whose lower end projects beyond said lever and bears against a bracket 21 provided therefor on the frame. This lever 19 extends above the piston rod 11 of the main cylinder 12 and is pivotally connected to the piston rod 18 of the lid positioning cylinder 15 at a point 22 near the free end of said lever. In the lower faces of the arms of said lever 19 are grooves 23 in position to receive the ends of the pivot pin 25 which 5 connects the main piston rod 11 with the ends of the hinge arm 5 of the trough lid when said main piston rod is in its uppermost position with the trough lid closed tight. On account of the point 10 22 of connection of said lever 19 with the piston rod 18 of the lid positioning cylinder being further from the fulcrum pin 9 than the point of connection of the main piston rod is from said fulcrum, coupled with the elasticity of the pressure fluid, the downward pull of the rod 18 on said lever 19 exceeds and overcomes the upward pressure 15 of the main piston rod 11 thereon with the result that the lever 19 moves downwardly until the adjusting screw 20 thereon bears against the limiting bracket 21. The effect of this movement 20 is that said lever 19 forces the main piston rod slightly downwardly carrying with it the outer end of the hinge lever 5 of the lid and thus swinging the lid up slightly.

Obviously, the construction hereinbefore described admits of considerable modification and I do not wish to be limited to the details described. The important consideration is that, after the trough shall have closed to straighten the billet and shall have held the billet tight while the 35 mandrel is being inserted thereinto, the lid shall be eased back far enough to permit easy sliding of the billet and shall still be held in its eased position to prevent whipping of the billet.

What I claim is:

- 40 1. In a billet handling device, the combination of a trough, a lid therefor, and means for operating said lid to wide open and clamping positions and means for releasing said lid from a clamping position to a released or guiding position.
- 45 2. In a billet handling device, the combination of a trough, an inverted trough shaped lid therefor hinged alongside of said trough, means for swinging said lid to wide open and closed positions and means for easing said lid from closed position without releasing the closing pressure.
- 50 3. In a billet handling device, the combination of a trough, a lid therefor hinged alongside of said trough, and means for exerting pressure elastically on said lid to swing said lid to wide open and closed positions and means for exerting greater pressure on said lid in opposition to the closing effort of said first means for easing said lid from closed position.
- 55 4. In a billet handling device, the combination of a trough, a lid therefor hinged alongside of said trough, and means for exerting pressure elastically on said lid to swing said lid to wide open and closed positions and means for exerting greater pressure on said lid in opposition to the closing effort of said first means for easing said lid from closed position, and means for stopping the easing movement of the lid.
- 60 5. A billet handling device comprising a frame, a trough on said frame, brackets on said frame alongside of said trough, a lid for said trough hinged on said brackets and having an arm extending beyond its hinge point, actuating means connected to said arm for opening and closing said lid, a lever hinged on said brackets and ex- 65 tends beyond the connection of said arm with

said actuating means, and means operatively connected to the free end portion of said lever and adapted to overcome the closing effort of said first mentioned means.

6. A billet handling device comprising a frame, 5 a vertically adjustable trough on said frame, brackets on said frame alongside of said trough, a lid for said trough hinged on said brackets and having an arm extending beyond its hinge point, actuating means connected to said arm for opening and closing said lid, a lever hinged on said brackets and extending beyond the connection of said arm with said actuating means, and means operatively connected to the free end portion of said lever and adapted to overcome the closing 10 effort of said first mentioned means.

7. A billet handling device comprising a frame, a trough on said frame, brackets on said frame alongside of said trough, a lid for said trough hinged on said brackets and having an arm extending beyond its hinge point, actuating means connected to said arm for opening and closing said lid, a lever hinged on said brackets and extending beyond the connection of said arm with said actuating means, means operatively connected to the free end portion of said lever and adapted to overcome the closing effort of said first mentioned means, and means for stopping said lever when the lid rises clear of the billet 20 25 30

8. A billet handling device comprising a frame, a trough on said frame, adjusting shims interposed between said frame and the bottom of said trough, brackets on said frame alongside of said trough, a lid for said trough hinged on said 35 brackets and having an arm extending beyond its hinge point, actuating means connected to said arm for opening and closing said lid, a lever hinged on said brackets and extending beyond the connection of said arm with said actuating means, and means operatively connected to the free end portion of said lever and adapted to overcome the closing effort of said first mentioned means.

9. A billet handling device comprising a frame, a trough on said frame, brackets on said frame 45 alongside of said trough, a lid for said trough hinged on said brackets and having an arm extending beyond its hinge point, a main pressure cylinder having a piston whose rod is connected to the free end portion of said arm for opening and closing said lid, a lever hinged on said brackets and extending beyond the connection of said arm with said piston rod, and a second pressure cylinder whose piston is connected to the free end portion of said lever and which is 50 55 adapted to overcome the closing effort of said first mentioned cylinder.

10. A billet handling device comprising a frame, a trough on said frame, brackets on said frame alongside of said trough, a lid for said trough hinged on said brackets and having an arm extending beyond its hinge point, a main pressure cylinder having a piston whose rod is connected to the free end portion of said arm for opening and closing said lid, a lever hinged on said brackets 60 and extending beyond the connection of said arm with said piston rod, a second pressure cylinder whose piston is connected to the free end portion of said lever and which is adapted to overcome the closing effort of said first mentioned cylinder, and means for stopping the easing movement of said lever at a predetermined 65 70 75 position.
